TIRE CHAIN

Draper M. Harvey, Hingham, Mass., assignor to
Earle B. Harvey and Associates, Boston, Mass.,
a partnership

Application March 24, 1948, Serial No. 145,321

Term of patent 14 years

(Cl. D90—20)

To all whom it may concern:

Be it known that I, Draper M. Harvey, a citizen of the United States, residing at Hingham, in the county of Plymouth and State of Massachusetts, have invented a new, original, and ornamental Design for a Tire Chain, of which the following is a specification, reference being had to the accompanying drawing, constituting a part thereof:

Fig. 1 is a side view of a tire chain, showing my new design;

Fig. 2 is a bottom plan view; and

Fig. 3 is a front elevation thereof.

I claim:

The ornamental design for a tire chain, substantially as shown.

DRAPER M. HARVEY.
